UNITED STATES PATENT OFFICE

JULIAN N. GIMENEZ, OF BROOKLYN, NEW YORK

STRETCHBOARD FOR DRAWING PAPER

Application filed August 20, 1930. Serial No. 476,692.

This invention relates to improvements in stretchboards for drawing paper.

Heretofore it has been the practice of artists when preparing a sheet of drawing paper for attachment to a drawing board, to wet both sides of the sheet and then blot the same about one or one and one-half inches from the edges thereof. Glue is then applied on the underside of the blotted area and the sheet placed down upon a drawing board but during the drying of the glue, the artist must pull the paper from all sides to tightly stretch the same before the glue has entirely hardened. This is a very long and tedious operation, and frequently the pull is not sufficient to successfully stretch the paper to the satisfaction of the artist, in which instances thumb tacks are resorted to. Of course drawing paper may be purchased in a stretched position upon a board, but this is very costly. It is therefore the aim of my invention to overcome these objections by providing a drawing board by which one unfamiliar in the art may quickly mount or demount a sheet of drawing paper upon a board, and when mounted thereon, the sheet will be tightly held in a stretched condition.

Another object of the invention resides in a stretcher board for drawing paper in which the side edges of the paper are held by removable clamping strips, and the strips in turn secured to the board proper by spring clips which in no way interfere with the free movement of the hand during drawing upon the paper, nor with the sliding movement of the T square should one be used in connection with the work.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a perspective view of my improved stretcher board showing one of the clamping members in separated position from the board.

Figure 2 is a greatly enlarged fragmentary

vertical sectional view on the line 2-2 of Figure 1.

Referring to the drawing by reference characters, the numeral 10 designates my improved stretcher board in its entirety which is constructed of three pieces of flat rectangular material, the lowermost piece being designated by the reference character 11, the intermediate piece by the numeral 12, and the uppermost piece by the numeral 13. These pieces 11, 12, 13 may be secured together by any suitable means such as by glue or by fastening elements, and are of various sizes for a purpose to be presently explained.

The intermediate piece 12 is of a size smaller than the base piece 11 and is positioned thereon so that the sides of the base piece 11 extend the same distances from all sides of the intermediate piece 12, in order to provide extending flanges 14. The uppermost piece 13 is of a size slightly greater than the intermediate piece 12, but considerably smaller than the base piece 11 so that all of the sides of the uppermost piece 13 extend equal distances from all sides of the intermediate piece 12 in order to provide overhanging flanges 15.

The flanges 14 constitute seats for the reception of the several clamping strips or bars 16, the same being of a length short of the length of the respective sides of the board, as best seen in Figure 1 of the drawing. These clamping strips 16 are of a thickness to fit between the overhanging flanges 15 and the flanges 14 with a thickness of paper clamped therebetween as shown in Figure 2, the said paper being designated by the reference character A. The top faces of the strip 16 are recessed inwardly from the outer longitudinal edges as at 17 to receive the upper leg 19 of U-shaped clamping elements or clips 18, the other legs of the clips engaging the under side of the lowermost piece 11.

In practice, a sheet of drawing paper slightly larger in area than the top surface 25 of the board 10 is wet in the usual way and placed over the flat top section 13 so that the edges of the paper A extend beyond the edges of the sections 13, it being understood that the clamping strips 16 and clips 18 are 100

removed from the board. After the paper has been so positioned, one of the strips 16 is placed in position so that one edge of the strip underlies the overhanging edge 15 of the top section 13, whereupon one edge of the paper is clamped between the strips 16 and beneath the flange 15, against the sides of the intermediate section 12 and against the upper side of the lowermost section 11. 5 The other clamping strips 16 are likewise applied to the respective sides of the board so that all sides of the paper are securely clamped and when so clamped, the paper assumes a tightly stretched position across the upper flat face of the board. It will now be seen that the paper is in condition to receive the work and there are no obstructions which might interfere with the free movement of the hands of the artist. In some cases it may be necessary to employ a T-square in connection with the work being performed and which instrument may be freely slid along the edges of the board without interference by the clamping clips 18 due to the fact that the upper legs of the same are countersunk in the top of the strips 16. 20 25

When it is desired to remove the paper from the board, it is only necessary to first remove the clamping clips 18 and then lift the several clamping strips 16 from clamping engagement with the edges of the paper. The paper is now free to be separated from the board, after which the edges may be crimped up to remove the creased areas 30 formed by the clamping strips.

Although wood is preferably used in the construction of the board, it will be understood that other material may be used if desired. Also, the board may be constructed of a single piece of material instead of the three pieces shown in the drawing, but the flanges 14 and 15 must be formed therein. 40

While I have shown and described what I deem to be the most desirable embodiment of my invention, I wish it to be understood that various changes in construction, may be resorted to if desired, and I do not limit myself to the exact details herein shown or described, nor to anything less than the whole of my invention limited only by the appended claims. 45 50

Having thus described the invention, what I claim as new and desire to secure by Letters Patent is:—

1. A stretcher board comprising a flat straight sided body, flanges extending from the sides of said body below the top surface thereof, flanges extending from the sides of said body and overhanging the first mentioned flanges, the top surface of said flat body adapted to receive a sheet of drawing paper to be stretched and held with its side edges extending beyond the sides of the top of said body, clamping strips seated upon the first mentioned flanges and disposed beneath 55 60 65 the overhanging flanges for securing the

edges of the paper therebetween, and clamping means for securing said clamping strips to said first mentioned flanges, substantially as and for the purpose specified.

2. A stretcher board comprising a flat straight sided body, flanges extending from the sides of said body below the top surface thereof, flanges extending from the sides of said body and overhanging the first mentioned flanges, the top surface of said flat body adapted to receive a sheet of drawing paper to be stretched and held with its side edges extending beyond the sides of the top of said body, clamping strips seated upon the first mentioned flanges and disposed beneath the overhanging flanges for securing the edges of the paper therebetween, and clamping means for securing said clamping strips to said first mentioned flanges, said clamping means being in the form of resilient spring clips, substantially as and for the purpose specified. 70 75 80 85

3. A stretcher board comprising three pieces of flat material secured one against the other, the intermediate piece having its side edges terminating short of the side edges of the lowermost piece, while the uppermost piece has its side edges extending beyond the side edges of the intermediate piece, clamping strips fitting upon the sides of the lowermost piece and beneath the extending edges of the uppermost piece, and clamping means for securing said clamping strips to said lowermost piece. 90 95 100

4. A stretcher board comprising a flat rectangular body having extending flanges on the sides thereof, overhanging flanges spaced from said extending flanges, clamping strips seated upon said extending flanges and beneath said overhanging flanges, and U-shaped resilient clips for clamping said clamping strips in position. 105

5. A stretcher board comprising a flat rectangular body having extending flanges on the sides thereof, overhanging flanges spaced from said extending flanges, clamping strips seated upon said extending flanges and beneath said overhanging flanges, and U-shaped resilient clips for clamping said clamping strips in position, one of the legs of said U-shaped clip being countersunk in recesses provided in the top sides of said clamping strips. 110 115 120

6. A stretcher board comprising a flat upper member, a lower member, the edges of which extend past the edges of said first member, and an intermediate member positioned between said upper and lower members, a clamping strip positioned between said upper and lower members, and clips to retain it in position. 125

In testimony whereof I affix my signature.

JULIAN N. GIMENEZ.
